BRACELET AND METHOD OF MAKING THE
SAME

Paul J. Bellavance, Attleboro, Mass.

Application January 28, 1937, Serial No. 122,767

4 Claims. (Cl. 29—160.6)

This invention relates to an improved bracelet and method of making the same, and more particularly to a bracelet structure in which the bracelet parts or sections are provided with connecting means firmly united thereto in a novel manner and so as to form a fixed union of the parts.

One object of the invention is to provide a bracelet structure of this character which is capable of being readily constructed at a relatively small cost, and one in which the parts are firmly held in operative relation with each other without the use of solder or separate attaching means.

Another object of the invention is the provision of a novel means for securing holding members to the bracelet sections in such a manner that they may be secured in place readily and retained firmly in position without danger of becoming loose or detached under ordinary conditions of use.

A further object of the invention is the provision of a new and improved method for forming devices of this character by means of simple mechanical operations which are capable of being readily carried out through easily operated mechanisms and without the necessity for specialized and time consuming operations.

Another object of the invention is the provision of novel means for readily securing a holding or other member in a channel shaped jewelry part without the use of separate holding means and in such a manner as not to mar the appearance of the article by the presence of unsightly attaching means upon any part of the structure.

Other objects and advantages of the invention relate to various improved details of construction and novel arrangements of the parts as will be more fully set forth in the detailed description to follow.

Referring to the drawing:—

Fig. 1 is a perspective view of an improved bracelet structure made in accordance with my invention.

Fig. 2 is a side elevational view of a portion of the inner surface of the bracelet shown in Fig. 1, showing the manner of attaching a hinge member to adjacent bracelet sections.

Fig. 3 is a similar view of a holding catch member showing the manner of attaching it to a bracelet section as seen from within the bracelet.

Fig. 4 is an enlarged detail sectional view through a portion of a bracelet section and holding member, showing the formation of the clamping lug and its relation with the parts.

Fig. 5 is a side elevational view, partially in section, of a portion of the operating mechanism of a power press such as may be employed in attaching the holding members to the bracelet sections, and.

Fig. 6 is a transverse sectional view through the mechanism shown in Fig. 5, taken substantially along the line 6—6 of Fig. 5.

In the embodiment of the invention illustrated herewith 1 designates generally a bracelet structure, which, as shown, may comprise two sections 2 and 3, although it may be made up of a greater number of sections if desired.

The sections 2 and 3 are each suitably curved to fit substantially the wrist of the wearer and are formed from channel shaped metal stock or are shaped to provide lateral flanges 4 located upon opposite sides thereof and extending inwardly from the inner curved surface of the member.

The bracelet sections 2 and 3 may be hingedly connected together by means of a hinge holding member 5 provided with a hinge joint 6 and having plates 7 extending from opposite sides of said hinge joint of such width as to fit substantially within the flanges 4. The plates 7 are firmly secured to the adjacent ends of the bracelet sections by having clamping lugs 8 swaged down from the inner surface of the flanges 4 into clamping engagement with portions of the plate 7 to clamp the hinged member firmly in position in the bracelet sections.

A holder catch member 10, provided with a portion 11 fitting closely within the flanges 4 of a bracelet section, is likewise secured to one bracelet section by similar clamping lugs 8 swaged down from the flanges 4 into clamping engagement therewith. The holder catch member 10 may be provided with an inclined detent 12 or similar part for engagement with a portion of another bracelet section provided by forming a recess therein as indicated at 14, the detent 12 being adapted to enter the recess 14 of the other bracelet section when the parts are closed to prevent their separation under ordinary conditions of wear. A chain 15 or other suitable connector may be attached to the bracelet sections adjacent to the free ends thereof for limiting the extent of movement of the bracelet sections when opened.

The hinge members 5 and catch member 10 are designated herein generically as holding members since they serve to hold the ends of the bracelet sections in position relative to each other and are similarly attached to the bracelet sections. While the holding members shown in the type of brace-

let illustrated herein are respectively a hinge and catch member adapted for connecting ends of the bracelet sections together, they may constitute any holding means such as may be employed in connecting the channel shaped section to another portion of a bracelet structure. Although one particular form of catch for uniting the ends of the bracelet sections is shown, any suitable catch structure may be employed for the purpose, it being understood that a portion of the catch element or elements may be adapted to fit within the flanges 4 of a bracelet section and be secured thereto by clamping lugs 8 after the manner described.

In forming the bracelet structure as above described the bracelet sections 2 and 3 may be formed in any suitable or desired manner, as by being cut or stamped out from a channel shaped strip of metal stock and then bent to obtain the desired degree of curvature, or the sections may be cut or stamped from flat stock and then treated in a suitable manner, as by means of dies, to obtain the desired curvature and form the lateral flanges 4 thereon. In either case the outer surfaces of the bracelet sections may be given any desired form of ornamentation, by stamping, engraving, engine turning, or otherwise, either in the form of metal stock prior to cutting and shaping the sections therefrom or at any time during the formation of the bracelet sections, as such, or after their completion.

The completed bracelet sections 2 and 3 after having been given the desired shape for incorporation into a bracelet and ornamented in the manner desired for the formation of the completed article are then secured together by the attachment of hinge members 5, each of which may be formed separately from the bracelet sections and provided with plate portions 7 shaped to fit against one side of adjacent bracelet sections and closely within the opposite flanges 4.

The manner of connecting holding members or the like to the bracelet sections may be accomplished by means of a power press or other suitable mechanism, after the manner indicated in Figs. 5 and 6 of the drawing. The mechanism shown therein comprises portions of a power press having a supporting plate or bed 20 and a plunger rod 21, which may be operated by any suitable power means (not shown). The supporting plate or bed 20 may be provided with a curved recess 22 formed in the upper surface thereof for receiving the bracelet sections, which recess is provided with a fixed wall 23 at one side thereof. A slidable holder member 24 is mounted in the bed 20 and provided with an end portion 25 forming the opposite side wall of the curved recess 22. Spring means 26 are mounted in the bed plate 20 for moving the slidable holder member 24 outwardly from the recess 22 when permitted by the plunger rod 21, said springs abutting against suitable shoulders or supports 28 which may be threaded into the outer ends of the spring receiving channels formed in the slidable member 24. The plunger rod 21 is provided with an inclined face 30 adapted to engage an inclined surface 31 carried by the slidable member 24 when the plunger rod 21 approaches the limit of its downward movement. The plunger rod 21 is also provided with a former head 33 having a lower surface 35 shaped to conform generally with the curve of the bracelet, and a transverse recess 36 formed therein adapted to receive the hinge joint 6. The opposite side faces 38 of the former head are shaped to fit closely

within the flanges 4 of a bracelet section and have cutting edges 40 for engagement with the flanges 4 to swage down therefrom clamping lugs 8 against the portions of a holder member fitted therebetween.

In the operation of this mechanism for forming the bracelet structure as above described, upward movement of the plunger rod 21 permits outward movement of the slidable member 24 under the influence of the springs 26 thus increasing the effective width of the recess 22 to permit it to receive readily the portions of a bracelet section or sections to be operated upon. The bracelet section or sections with a holding member or members suitably located therein may be inserted in the recess and the plunger rod operated to move the former head 33 downwardly.

As the plunger rod approaches the limit of its downward movement the inclined face 30 engages the inclined surface 31 on the slidable member 24 to force the slidable member 24 towards the recess 22 and bring the end portion 25 of the slidable member into close abutting relation with the outer face of one of the flanges 4. The plunger rod then completes its downward movement bringing the cutting edges 40 downwardly against the flanges 4 to cut out and force downwardly the clamping lugs 8 against those portions of the holder member located within and adjacent to the flanges 4. This portion of the operation takes place while the opposite flanges 4 are firmly supported outwardly by the side wall 23 of the recess and the end portion 25 of the slidable member, and at the same time the inner sides of the flanges 4 are supported generally adjacent to the cutting edges 40 by the opposite side faces 38 of the former head. In this way a substantially complete support is provided for the flanges 4 while the cutting edges 40 are operating thereon to prevent any bending or distortion of the flanges during the swaging operation. Upon upward movement of the plunger rod 21, the slidable member 24 again moves outwardly under the influence of the springs 26 and the bracelet sections may be removed without binding against the side walls of the recess.

This method of securing parts to the bracelet sections may be followed both in connection with the attachment of the hinge member and catch holder member shown as well as any other form of reinforcing, attaching or holding member which it may be desired to secure in a bracelet section or jewelry element of the general form and character of the bracelet sections shown.

What I claim is:—

1. A bracelet structure comprising two or more longitudinally curved sections having lateral flanges inbent from flat stock of uniform thickness to form internal channels therebetween, holding members connecting adjacent ends of said bracelet sections and each having a portion fitting within the internal channel of one of said sections and abutting against the lateral flanges carried thereby, and clamping lugs struck down from said flanges engaging portions of said holding members for securing each holding member firmly to a bracelet section.

2. The method of forming a bracelet structure which comprises, shaping metal stock to form a curved section having lateral flanges, fitting a portion of a holding member between the lateral flanges adjacent to an end portion of said section, and striking down portions of the lateral flanges upon the part of said holding member fitted between the flanges to clamp said holding member

- to said section while supporting the lateral faces of said flanges at points adjacent to the struck down portions.
3. The method of making a bracelet structure which comprises, forming curved sections having lateral flanges extending from one side thereof, fitting portions of a holding member between the lateral flanges adjacent to certain of the end portions of said sections, and striking down portions of the lateral flanges upon the portions of said holding member fitted therebetween while providing a support for the outer faces of the flanges to secure said holding member to said sections while at the same time preventing distortion of the flanges.
4. The method of forming a bracelet structure or the like which comprises, shaping metal stock to form a section having upstanding lateral flanges, fitting a portion of a member between the lateral flanges, and swaging down portions 5 of the lateral flanges upon the part of said member located between the flanges to form clamping lugs and secure said member to the section while supporting said lateral flanges both outwardly and inwardly at points adjacent to the clamping lugs during the swaging operation to prevent distortion of the flanges during the formation of the clamping lugs. 10

PAUL J. BELLAVANCE.
